(57) **CLAIM**

The ornamental design for an audio and charging station for a handheld electronic device, as shown and described.

DESCRIPTION

FIG. 1 is a top perspective view of an audio and charging station for a handheld electronic device showing our new design;

FIG. 2 is a perspective view thereof;

FIG. 3 is a front elevational view thereof;

FIG. 4 is a side elevational view thereof, the opposite side being a mirror image;

FIG. 5 is a top plan view thereof;

FIG. 6 is a cross-sectional view taken along line 6—6 in FIG. 3;

FIG. 7 is a cross-sectional view taken along line 7—7 in FIG. 3; and,

FIG. 8 is a front elevational view thereof, shown with a broken line rendering of a handheld electronic device shown mounted in the station.

The broken line showings of the rectangular areas and the circles on the front of the station in all of the figures, and the handheld electronic device in FIG. 8 are for illustrative purposes only and form no part of the claimed invention.
